WATER SPRAY SKIRT FOR AN AERATOR

Irving A. Ward, 2709 La Cuesta Ave.,
Hacienda Heights, Calif. 91745

Filed Jan. 7, 1972, Ser. No. 216,319

Term of patent 14 years

Int. Cl. D23—01

U.S. Cl. D23—35

FIG.—1

FIG.—2

FIG.—3

FIG.—4

FIG. 1 is a perspective view of a water spray skirt for an aerator showing my new design;

FIG. 2 is a plan view thereof;

FIG. 3 is a bottom view thereof; and

FIG. 4 is a side view thereof.

I claim:

The ornamental design for a water spray skirt for an aerator, substantially as shown.
